UNITED STATES PATENT OFFICE.

JOSEPH JACOBS, OF SAN FRANCISCO, CALIFORNIA.

SWIMMING DEVICE.

1,159,945.

Specification of Letters Patent.

Patented Nov. 9, 1915.

Application filed May 21, 1914. Serial No. 329,994.

To all whom it may concern:

Be it known that I, JOSEPH JACOBS, citizen of the United States, residing in the city and county of San Francisco, State of California, have invented certain new and useful Improvements in Swimming Devices, whereof the following is a specification.

This invention relates to improvements in swimming devices, and more particularly to apparatus mechanically propelled by the swimmer.

Among the objects of this invention are: To provide a boat-like float adapted to support the weight of the operator and to add to such float mechanical means operated by the swimmer to propel the boat. To provide means for steering the apparatus laterally as well as downward.

Other objects and advantages will appear as the description progresses.

The drawings, consisting of a single sheet, accompanying and forming part of the present specification, have corresponding reference characters applied thereto, and illustrate the preferred means for putting this invention into practice.

In the drawings: Figure 1 is a plan view from above of the swimming device constructed in accordance with this invention. Fig. 2 is a side elevation of the same as it appears supporting the weight of the operator in the proper position to operate the device to the best advantage. Fig. 3 is a cross section taken on the line a—a of Fig. 1, looking toward the rear end of the device.

In detail the construction illustrated in the drawings includes the hull, 1, comprising the main frame, 2, having the ribs, 3, and 4, extending across the main frame to receive the proper impervious covering, 5, such as rubberized fabric or the like; producing in effect, a decked over canoe-like structure, shaped to fit the anatomical outlines of the swimmer; to produce the requisite buoyancy in the minimum of space, and 6 and 6 are pontoons secured, one on each side of the hull, 1.

In operation the hull is completely submerged, as indicated by the waterline, A, shown at Fig. 2, while the pontoons preferably float about one third out of water. These pontoons are preferably constructed to be inflated to any desired distention to aid in properly balancing the craft, according to the distribution of weight in the body of the operator. The propelling mech-

anism includes the frame composed of the side rails, 7 and 7, with the end rail, 8, between. The side rails, 7, are properly attached to the hull, 1, preferably to the main frame, 2. The crank shaft, 9, is journaled in the side rails, 7 and 7, and has the cranks, 10 and 10, fixed thereon, on diametrically opposite centers, and are provided with the pedals, 11 and 11. The main driving gear, 12, is fixed on the crank shaft 9, and enmeshed with the beveled pinion, 13, fixed on the shaft, 14, also suitably journaled in the end rails, 8, and the propeller, 15, is fixed on the shaft, 14. The steering gear includes 70 the rudder, 16, preferably conical, tapering from the point, 17, in streamline contour to the stem, 18. The stem, 18, is provided with a ball-shaped end engaging the socket, 19, to form a ball-joint, having the necessary range of action about its axis, to steer the machine laterally, to right or left, or downward, as in diving. The rudder is controlled by the handles, 20 and 20, to be grasped by the operator as he lies prone on 80 the hull. The operator lies on the hull as shown in Fig. 2, between the pontoons, which float above the center of gravity, to give the proper balance to the machine. Grasping the rudder handles for steering, 85 the operator places his feet upon the pedals, 11 and 11; by pedaling as in bicycle riding the driving mechanism imparts rotation to the propeller, 15, to propel the hull through the water in any direction controlled by the steering gear.

Having thus described my invention, and an embodiment of it, in the full, clear, and exact terms required by law, and knowing that it comprises novel, useful and valuable improvements in the art to which it pertains, I here state that I do not wish to be limited to the precise construction and arrangement of the several parts, as herein set forth, as the same may be variously modified by a skilled mechanic without departing from the spirit of the invention.

What I claim and desire to secure by Letters Patent of the United States is the following, to wit:

1. In a swimming machine, a hull provided with buoyant means and pedal driven propeller secured to the rear end of said hull, a cone shaped steering means movably secured to the front end of said hull and provided with hand controlling means centrally secured on the sides thereof.

2. In a swimming machine, a hull provided with pontoon adapted to support the operator in a prone position, a frame secured to the rear end of said hull provided with manually driven propelling means and a cone shaped steering means secured to the front end of said hull by a universal joint.
3. In a swimming machine, a hull provided with buoyant means secured to the side thereof and adapted to support the operator in a prone position, a frame secured to the rear end of said hull and provided

with a pedal crankshaft having a propeller and a steering rudder having a cone shape, secured at its rear end to the front end of said hull by a ball and socket.

In testimony that I claim the foregoing I have hereto set my hand in the presence of two witnesses, this 16th day of May, 1914.

JOSEPH JACOBS.
